UNITED STATES PATENT OFFICE.

JOHN W. ELLIS, OF PORTLAND, MAINE.

VENTILATOR.

No. 909,381.

Specification of Letters Patent.

Patented Jan. 12, 1909.

Application filed January 29, 1908. Serial No. 413,230.

To all whom it may concern:

Be it known that I, JOHN W. ELLIS, a citizen of the United States, residing at Portland, county of Cumberland, State of Maine, have invented certain new and useful Improvements in Ventilators, of which the following is a specification.

This invention relates to ventilators and more particularly to a ventilator for use in a window. In ventilators of this sort it is extremely desirable to secure a steady and free current of air without having it occur as a direct draft or blast and for this purpose I have devised my present invention in which I have provided for securing this result in a convenient and efficient manner and by means which are simple, and structurally strong and stable. These means involve the employment of parts so disposed as to cause an indirect draft by means of deflecting agencies the structure of which will be more fully set forth in the specification and will be illustrated by the disclosure of an embodiment of my invention in a form particularly adapted to be inserted between the lower sash of a window and the window sill for allowing a current of air to pass through to secure the ventilation of a room. This I have illustrated in the drawings which form a part of the specification being made a part thereof by reference and by means of reference numerals applied to the various parts uniformly throughout both.

In the drawings Figure 1 is an outside elevation in place, Fig. 2, an inside elevation in place and partly in section, Fig. 3, a top plan view of my ventilator, and Fig. 4, a vertical section of ventilator in place.

1, 2, 3, and 4 are the top, outside, bottom, and inside walls of a ventilator. The top wall 1 is provided with a strip 5 against which the lower bar 6 of the sash rests to prevent drafts, while the outer wall 2 is carried down below the bottom 3 to form a projecting flange which will coöperate with the edge of the window sill to make a draft shield along the line of meeting between ventilator and sill 7. The outer wall 2 is slotted as at 8 and in case of broad windows I leave between the ends of slots supporting sections 2¹. These slots are covered by a screen 9 the arrangement of which I will describe later. The top wall 1 is pierced by a series of apertures 10 which correspond with ports 11 in a slide 12 which is moved

by a knob 13 projecting through a slot 14 in the top 1, and about midway thereof.

Below the openings 8 in the outside wall 2 is formed a vertical groove 16 and in the front or outer edge of the bottom 3 and 60 opposite to the groove 16 is formed a similar groove 15 which with the groove 16 forms a tubular drain for any moisture which may beat into the ventilator through the screen 9 of the openings 8. The lower edge of the 65 screen 9 is laid between the forward edge of the bottom wall 3 and the inner face of the outer wall 2 in the assembling of the parts. On the internal face of the inside wall 4 is a kerf in which are set a plurality 70 of deflecting strips 17 which lie in front of the apertures 10. The ends of these strips bear against the upper edge of the screen 9 and press it against the internal face of the outside wall, thus holding it firmly in place 75 over the openings 8.

18 are handles for convenience in putting the ventilator in place or removing it from window if it is desired to do so although on account of the closing slide 12 it is not necessary to remove the ventilator even in the severest weather.

As will be seen the ventilator may be easily made in any length desired and affords a simple and efficient structure. The 85 embodiment shown and described might obviously be varied without departing from the spirit of my invention. It is also obvious that this ventilator might be applied in the same manner or in a modified form for use 90 at the top of a window or in a similar situation. In preparing a ventilator for use at the top of a window it would be desirable to have the openings 10 in the inside wall 4 instead of on the top 1. In this arrangement 95 the openings 10 would be located above the plane of the transverse deflector 17 around which the air current would have to pass, as before described.

What I therefore claim and desire to secure by Letters Patent is:

1. A ventilator comprising a longitudinal chamber having an opening in one side thereof for communication with the outside and a plurality of openings in the top for communication with the room and a plurality of deflectors within said chamber one in front of each of said last named openings said deflectors being spaced apart to allow a current of air to pass between them. 110

- 2
2. A ventilator comprising a longitudinal chamber having an opening in one side thereof and an opening in the top, a screen over said first named opening, and a deflector within said chamber in front of said last mentioned opening, the end of said deflector bearing against said screen to hold it in place.
3. A window ventilator comprising a longitudinal chamber having an opening in one side thereof for communication with the outside and a plurality of openings in the top for communication with the room, a plurality of deflectors within said chamber one in front of each of said last named openings said deflectors being spaced apart to allow a current of air to pass between them, and a slide for opening or closing said openings in the top.
4. In a ventilator box having oppositely

disposed walls and an intake opening in one wall, a groove in the opposite wall and a screen over said opening, and a deflector strip in said groove and bearing with its end against the edge of said screen.

25

5. In a ventilator of the class described having a plurality of vertically disposed escape openings and a plurality of horizontally disposed intake openings, a plurality of deflector plates disposed in the direct lines between said openings, but spaced apart to allow the passage of a current of air between said plates.

30

In testimony whereof, I affix my signature in presence of two witnesses.

JOHN W. ELLIS.
